UNITED STATES PATENT OFFICE.

STUART W. WEBB, OF BROOKLINE, MASSACHUSETTS, AND ALBERT ALLEN, OF BANGOR, MAINE, ASSIGNEES TO EASTERN MANUFACTURING COMPANY, OF BOSTON, MASSACHUSETTS, A CORPORATION OF MASSACHUSETTS.

METHOD AND MECHANISM FOR MARKING AND FINISHING PAPER.

Application filed April 28, 1926. Serial No. 105,124.

This invention relates to a method and mechanism for marking paper by which a mark closely simulating a water mark can be made while the paper is having imparted thereto a finish such as the well known linen finish.

One method by which linen finish may be imparted to paper is disclosed in Patent No. 1,277,714 granted September 3, 1918, and while this invention is not limited thereto, it is particularly suitable for use in connection with that process.

The process as disclosed in that patent comprises, in general, passing the paper interposed between a pair of textile belts through the nip between a pair of rolls, one of which is softer than the other, these rolls being held together under heavy pressure. By the use of the relatively hard and soft rolls a slight slip between the paper to be finished and the textile belts is produced, as fully described in that patent, this slip producing the desired polish of the paper.

According to the present invention the marking is effected by passing through the nip with the paper and belts a relatively thin pattern member cut to the form of the desired mark, it being found in practice that this member may well be formed of thin paper. It may be fixed to the surface of one of the rolls, to the surface of the belt, or between the plies of a multi-ply belt. In order not to obliterate the fabric finish over the marked portions, the marking member should not contact directly with the paper to be marked, but should have at least one ply of the fabric between, though of course where no fabric finish is desired on the marked portion, the marking member might be passed in direct contact with the paper to be marked.

By this method also marking of quite different character from the usual water marks may be produced, if desired, by suitably forming the marking member. For example, paper perforated to produce ornamental designs of any desired character may be employed as a marking member the paper being marked then showing therein the design produced by the perforations, or if desired paper of variable thicknesses or a plurality of layers of paper having non-registering perforations may be employed to further diversify the mark produced. Gener-

ally, however, the total thickness of the marking member should not greatly exceed that of a fairly heavy paper. The degree of conspicuity of the mark may be regulated to some extent by the thickness of the marking member and also by its nearness to direct contact with the paper to be marked.

For a more complete understanding of this invention reference may be had to the accompanying drawings in which

Figure 1 represents a cross section through the hard and soft roll of a fabric finishing machine of the type disclosed in the patent hereinbefore referred to and showing the textile belts and paper passing through the nip between these rolls and illustrating one portion of the marking members.

Figure 2 is a similar view showing another position of the marking members.

Figure 3 is a cross section through one of the rolls showing the marking members fixed thereto.

Referring first to Figure 1, 1 and 2 indicate respectively the soft and hard rolls of the continuous process linen finish machine. The paper to be finished is indicated at 3 which passes between the fabric belts 4 and 5. As therein shown these fabric belts are multi-ply belts and the marking members shown at 6 are fixed between the plies of the belt 4, there being one ply of fabric between these members and the paper to be marked.

In Figure 2 the soft and hard rolls are indicated at 10 and 12, respectively, the paper 3 being passed between the textile belts 14 and 15. The marking elements are shown at 16 and as here shown they are fixed to the inner face of the belt 14 so that they come into direct contact with the surface of the hard roll 12, all the plies of the textile belt 14 coming between them and the paper 3 which is to be marked.

In Figure 3 one of the rolls only is shown at 20 and the marking members at 21 are fixed directly to its surface. This construction is similar in action to that shown in Figure 2 in that all the plies of the belt which are passed in contact with the roll are interposed between the marking element and paper to be marked. The thickness of the marking members in these figures is considerably exaggerated in order that it may be shown, as a matter of fact best results

being secured by the use of paper of not unusual thickness, and while as shown the members are relatively small pieces positioned at intervals they might comprise 5 more or less continuous sheets perforated with any desired pattern. It is usually better to have the marking member on the same side of the paper to be marked as is the harder roll.

10 Having thus described certain embodiments of this invention it should be evident to those skilled in the art that various changes and modifications may be made therein without departing from its spirit or 15 scope as defined by the appended claims.

We claim:

1. The method of imparting a fabric finish to paper and marking the paper, which comprises subjecting the paper interposed 20 between fabric layers together with a marking element to heavy pressure and simultaneously effecting a slight slip between the paper and fabric.
2. The method of imparting a fabric finish to paper and marking the paper, which comprises passing the paper interposed between fabric layers and with a marking element through the nip between a pair of rolls, one of said rolls being softer than the other.
3. The method of imparting a fabric finish to paper and marking the paper, which comprises passing through the nip between a

hard and a soft roll the paper to be treated interposed between fabric layers and with a marking member spaced from the paper 35 by a ply of one of said layers.

4. The method of imparting a fabric finish to paper and marking the paper, which comprises passing through the nip between a hard and a soft roll the paper to be treated 40 interposed between fabric layers and with paper cut to the desired marking spaced from the paper to be finished by a ply of one of said layers.

5. A mechanism for finishing paper comprising a pair of layers of fabric between which the paper to be finished may be interposed, a pair of rolls one softer than the other through the nip between which said 45 layers of fabric pass, and a marking member constructed and arranged to be passed through said nip with said fabric layers and the paper to be finished.

6. A mechanism for finishing paper comprising a pair of rolls one roll being harder 50 than the other and through the nip between which the paper to be finished may be passed, and a marking member fixed to the periphery of one of said rolls.

In testimony whereof we have affixed our 55 signatures.

STUART W. WEBB.
ALBERT ALLEN.
